FIRE ALARM SYSTEM

Dempsey Coleman, Fairbluff, N. C.

Application May 26, 1947, Serial No. 750,532

2 Claims. (Cl. 169—23)

1

This invention relates to fire alarm systems and it has for its main object to improve fire alarm systems such as used in hotels, apartment houses and other structures with a number of separate and guarded units which are provided with a central alarm station having an indicator with electric warning signals automatically operated by fire responsive devices in said units.

As a rule, the device located in the guarded room or unit for operating the electric warning signal in the central alarm station consists either in a thermostat or in a fuse; both these devices have the disadvantage that they can be adjusted merely for relatively high temperatures and that they are located at a given point within the room to be guarded. In the event of a fire a relatively long time may elapse until the point at which the device is mounted reaches the critical temperature. This time together with the time necessary to reach the premises from which the alarm signal issues and for bringing counter measures into action, is as a rule so long that such counter-measures on a relatively small scale are no longer effective.

It is therefore an object of the invention to provide means for giving the alarm signal at the earliest possible stage and it is a further object to provide additional means for bringing the countermeasures automatically into effect at such an early stage. The means for operating the countermeasures which may preferably consist in a chemical fire extinguisher may be the same means which operate the alarm signal or may be different means which are differently operated and located.

A further object of the invention consists in distributing the said means and in arranging them in a such a way that they are likely to operate in the initial stage wherever flames are originating on the premises to be guarded. These means may themselves either alone or in conjunction with a temperature responsive device control the automatic operation of the extinguishing means.

Further objects of the invention will be made apparent from the following detailed specification.

The invention is illustrated in the accompanying drawings showing one embodiment of the same. It is however to be understood and will be clear to the expert skilled in this art that the same principles may be realized with modifications of the embodiment shown, so that such modifications do not necessarily indicate a departure from the invention.

2

In the drawings:

Figure 1 is a diagram showing the various parts of the system and their connections;

Figure 2 is a similar diagram showing the details of the connections;

Figure 3 is a partly sectional elevational view of the head of a chemical fire extinguisher provided with an automatically releasable stopper;

Figure 4 is a detailed view of the twisted wires used as a flame indicator;

Figure 5 is a diagrammatic view of the thermostatic device and of the relay controlling the heavy amperage current.

According to the invention the fire alarm signal is produced either by open wire loops 10 or by a thermostat 30. The wire loops 10 consist of two wires 12 provided with cotton insulation, which is waxed or impregnated with paraffin and a pair of such wires are insulated from but are twisted around each other as indicated in Figure 4. Thus an open loop is produced which is placed around doors or windows or around other openings. If necessary it may run around the room or other protected unit, say near the ceiling and/or near the bottom. The insulated wires 12 of the loops 10 carry currents under low tension, for instance under the tension of a battery or of an A. C. produced by means of a step down transformer. It has been found by experience that the insulation of the wires will be kindled and burn as soon as a flame reaches the wires, even if the temperature produced by the flame is comparatively low. As flames developing in the case of fire invariably produce a draft and have a tendency to reach the door or window, on account of the pressure which develops in a highly heated room and which produces a leakage, wires laid around these openings will be reached by the flames shortly after they originate. The wire loops, as a matter of course, are placed near other openings such as a fireplace, an opening provided for ventilation, an exit opening in the roof or floor and the like, wherever a room happens to be provided with these types of openings.

The wires used for alarm purposes may be of the customary one layer bell wire type with a single layer of impregnated and coated cotton or may be specially prepared, so as to make the insulation more easily combustible. The cotton insulation burns almost completely without leaving ashes once it has been kindled by a flame, and upon disappearance of the relatively thin insulating layer the wires on account of the firm twisting around each other, come into electric

contact, so that the loop is converted into a closed connection.

The loops of one room may all be connected in parallel and are branching off from two conductors 15a, b, c, 16a, b, c, one of which (16) is connected with a common lead 17 joined to a return conductor 18 which leads back to the battery 19 or other source of current.

The wires 15a, 15b lead to conductors 25 connecting them with the indicator board 28 of a central station 20 arranged at some central supervised point. This indicator board is provided with indicator signals and indicator relay sets 21, by means of which an optical signal 23 (indicated as a lamp for example) may be given. The specific construction of the set and of the board is immaterial as any approved construction may be used; the specific construction of the central board signal sets shown in Figure 2 is without specific significance for the invention.

In addition to the optical signal 23 an acoustical signal such as a buzzer, an alarm bell 24 or the like may be arranged, preferably in a part of the circuit which is common to all indicator sets so that an acoustic alarm signal will be given simultaneously with every optical signal.

In addition to the loops 10, 10' thermostats 30 are provided reacting, as is customary, to the temperature which is imparted to them by radiation or to the temperature acquired by the ambient air. These thermostats may either act independently or they may be operative conjointly with the loops to provide a kind of check on conditions in the room to be protected as described later. These thermostats control a circuit 31 which may be a branch of the low tension circuit or a circuit 31a which carries high amperage currents. The former contains a relay 32, capable of controlling a circuit 33 carrying heavy currents derived from a network 35; the network may be identical with the power supply network of the building. The relay 32 is provided with contacts 36 opening and closing circuit 33. The latter includes the chemical fire extinguisher 37.

As soon as the thermostat operates the chemical fire extinguisher which is of the type containing a liquid or gas under pressure and spraying either extinguishing gases or an extinguishing liquid or an extinguishing foam, is operated in a manner described below and therefore as soon as a dangerous temperature is reached in the protected room countermeasures aiming at the fighting or extinguishing of the fire are initiated. These countermeasures will either extinguish the fire or keep it more or less in its initial stage until the room is reached by the personnel which has been alarmed by the signal on the switchboard.

The details of the connections and of the operating mechanisms are illustrated in Figures 2, 3 and 5. Figure 3 shows the way in which the chemical fire extinguisher 37 is brought into operation. The said fire extinguisher has customarily a head 38 and is closed by a valve or a similar appliance, the casing of which is screwed to the head. This appliance is removed and disk 40 with a combustible central portion is substituted which is firmly held against the orifice of the duct 42 leading through the head by means of a sleeve 39 screwed into the head 38. This sleeve, in addition to the internal screw threads provided for fixing it on the head carries also external threads which serve to screw over it a

cylindrical casing 44, carrying two terminals 45, 46 to which the wires of the heavy amperage circuit 33 controlled by relay 32 may be fixed. Between these terminals a fuse wire 48 is inserted, which becomes incandescent upon the passage of a short circuit current and melts after a short while. This wire extends across the casing 44 which is completely filled either with a combustible material, or with an alloy melting at a very low temperature. This material forms a stopper 49 arranged above the disk 40 and melts under the influence of the heat produced in the fuse wire 48 or is consumed by combustion. The opening 51 of the casing 44 may be closed by a combustible disk 52 holding the stopper 49 in its position. The central portion of disk 40 likewise may be made of an alloy material which melts at a low temperature. The duct is thus freed when the stopper melts and drops and the liquid or gas under pressure contained in the extinguisher 37 is sprayed.

As explained it may be advisable to operate the fire extinguisher solely by means of the thermostat 30 or alternatively when the loop is short circuited or when the thermostat operates following a short circuiting of one of the loops 10, 10'. The connections for all these cases are shown in Figure 2 in the compartments a, b, c. The last mentioned case is advisable because a short circuit in the loop may occur without any fire. On the other hand a thermostat may be adjusted to a much lower temperature if it operates with a flame operated device.

The thermostat 30 shown in Figure 5 is preferably of the customary bellows type, expanding when heated with the air temperature. It operates a contact 54 which closes the relay circuit 33. The relay 32, in its turn, controls the circuit 55 carrying a current of relatively high amperage.

The relay 32 may be dispensed with when the thermostat alone controls the current through the fuse, as indicated in compartment a in Figure 2.

The diagram shown in Figure 2 will be readily understood from the foregoing description. A short circuit in the loop due to the burning of the insulation of the wires 12, causes a current to flow from the source of current 19 (battery or low voltage secondary) through the relay 22 of the switchboard 28 and through lamps 23 to the conductor 15a in the compartment or room a. The circuit in this case is closed through the loop 10 or 10' when the insulation burns and connection is established over conductors 16a, 17 and 18 to the source of current or battery 19. This will light the signal lamp 23 and operate the indicators 29 and the acoustic signal 24.

The thermostat 30 in compartment a operates independently when the room temperature reaches the desired limit. It closes the heavy amperage circuit 31a and thereby produces a melting or combustion of the stopper 48 of the extinguishing device 37.

In the compartment b the closing of the loop circuit 10 or 10' produces an operation of the relay 32, by means of conductors 25b and 15b energized in the manner already explained, over conductors 16b, 17 and which are connected with return connector 18. The energization of relay 32 then closes the circuit 33 through the incandescent fuse wire melting the stopper of the fire extinguisher.

This operation will also occur when the thermostat 30 operates because the room temperature has risen to an undesirable degree, irrespec-

tive of the closing of the loop. The circuit through the relay 32 is in this case closed over conductors 25b and 26, 17 and 18.

In compartment c the fire extinguishing relay 32 is merely operated, if the loop and the thermostat are both operated thus checking each other's correct function. The circuit is again running from conductor 25c over the relay 32 and the thermostat contacts 54 to conductor 15c and over the loop 10 or 10' to conductor 16c and conductors 17 and 18.

It will be readily understood that changes in the constructive details or connections will not affect the alarm system according to the invention.

Having described the invention, what is claimed as new is:

1. A fire alarm system for the remote indication of the outbreak of a fire in a protected area and for the operation of extinguishing means in said area, comprising a source of alarm current, an alarm circuit including at least one flame responsive open loop circuit, consisting of twisted insulated wires with inflammable insulation, said loop circuit being located in the above named protected area, and closing a branch of the said alarm circuit when exposed to a flame, a heat responsive thermostatic device in said protected area with contacts closing a branch of said alarm circuit when the said thermostatic device is operated, a fire extinguisher provided with a temperature responsive fusible stopper in said protected area, a fuse wire arranged within said stopper adapted to melt said stopper when heated, a fuse wire circuit, a relay having a winding arranged within said alarm circuit controlling the admission of current to said fuse wire and fuse wire circuit, and a source of heavy currents supplying said fuse wire circuit.

2. A fire alarm system for the remote indica-

tion of the outbreak of a fire in a protected area and for the operation of extinguishing means in said area, comprising a source of current, an alarm circuit, including flame responsive open loop circuits consisting of twisted insulated wires with inflammable insulation, said loop circuits being located in the above named protected area and forming parallel branches of the said alarm circuit, a heat responsive thermostatic device located in the aforesaid protected area with thermostat contacts arranged within a branch of the alarm circuit, connected in series with the branches containing the loop circuits and therefore closing said alarm circuit jointly with one of the loop circuits, a fire extinguisher in said protected area provided with a temperature responsive fusible stopper, a fuse wire arranged within said stopper to melt the stopper when heated, a fuse wire circuit, a relay, having a winding arranged within the alarm circuit and controlling the admission of current to said fuse wire and fuse wire circuit, and means for supplying the last named fuse wire circuit with heavy current.
